UNITED STATES PATENT OFFICE.

GEORGE D. GALLAGHER, OF WASHINGTON, DISTRICT OF COLUMBIA, ASSIGNOR TO
WINCHESTER REPEATING ARMS COMPANY, OF NEW HAVEN, CONNECTICUT,
A CORPORATION OF CONNECTICUT.

HANDLAMP-SWITCH.

1,396,829.

Specification of Letters Patent.

Patented Nov. 15, 1921,

Application filed June 8, 1920. Serial No. 387,278.

To all whom it may concern:

Be it known that I, GEORGE D. GALLAGHER, a citizen of the United States, residing at Washington, District of Columbia, have 5 invented certain new and useful Improvements in Handlamp-Switches; and I do hereby declare the following to be a full, clear, and exact description of the invention, such as will enable others skilled in 10 the art to which it appertains to make and use the same.

The present invention relates to battery hand lamps of the kind in which a battery and a small incandescent lamp are mounted 15 in a casing together with suitable switch mechanism for controlling the flow of current from the battery through the lamp.

The objects and advantages of the present invention will become clear from the following detailed description, taken in conjunction 20 with the accompanying drawings, wherein one embodiment of the present invention is described and illustrated.

In the drawings, Figure 1 is a fragmental, 25 sectional elevation of a complete hand lamp of the flat or vest pocket type; Fig. 2 is a fragmental, longitudinal section showing the switch mechanism closed; Fig. 3 is a similar view with the switch mechanism 30 in safety position; Fig. 4 is a plan view of the switch mechanism; Fig. 5 is a sectional elevation on the line 5—5 of Fig. 1; Fig. 6 is a similar section on the line 6—6 of Fig. 1; Fig. 7 shows the slots cut in the side of 35 the metal case; Fig. 8 is a plan view of the housing by which the push-button contact is moved along the double key hole slot of Fig. 7; Fig. 9 is a detail of the leaf spring and the push-button mounted thereon.

40 In the embodiment illustrated, the hand lamp comprises a case 1, which may be of metal, and flat, as shown. At the front end of this case and threaded thereto is a lamp 2, the inner terminal 3 of which makes contact with the longer terminal 4 of a battery 5 positioned within the case. This battery has a short exposed terminal 6 at which the battery circuit through the lamp is controlled. One of the rounded edges of case 45 1 is cut or punched to form guideways 7 and 8 (Fig. 7) and a tongue or finger 9 between these guideways is severed at its front edge 10 but left integral with the case at the rear edge, and is pushed down into

the position shown in Fig. 1 to serve as a 55 resilient battery retaining finger. This finger not only positions the battery within the case, but keeps it from rattling around. There is also provided a double key hole slot (Fig. 7) consisting of a large round 60 opening 11, a narrower opening 12, a second large round opening 13, and a narrow bottom end 14.

Mounted to slide along case 1 is a thumb-actuated housing 15 having integral tangs 65 16 and 17 for engagement with slots 7 and 8, respectively, and having a round opening near its front end in which is housed a push-button 18. Mounted within housing 15 and secured thereto at one end, as 70 by a rivet 19, is a leaf spring 20 (Fig. 9).

At the front or free end of leaf spring 20 is mounted a push-button contact element 75 comprising push-button 18 and a central stud, the upper reduced end 21 of which passes through spring 20 to the outer rounded face of push-button 18 where it is riveted over to hold the three parts together. The lower reduced end 22 of the stud can be brought into contact with battery terminal 6 to close the battery circuit 80 through the lamp. The stud has a tapered enlargement 23 of a size to fit loosely in openings 11 and 13 of the double key hole slot, and above this is a cylindrical portion 85 24 having a diameter comparable to the narrow portions 12 and 14 of the key hole slot.

The push-button contact, as above described, and as illustrated in Fig. 1, is movable by thumb pressure on button 18 90 into and out of contact-making engagement with the exposed terminal 6 of the battery to control the flow of current from battery 5 through lamp 2, but the sliding movement of the housing and the co-operation 95 of the double key hole slot with the enlargement 23 on the push-button stud, effect new and desirable results, as hereinafter explained more in detail.

With the switch mechanism positioned 100 as in Fig. 1, the enlargement 23 of the push-button contact rests in the enlargement 13 (Fig. 7) of the key hole slot, and the resiliency of spring 20 holds the button in its outer position. In this position the 105 push-button contact is not in engagement with the exposed battery terminal 6, but by thumb pressure on button 18 can be

pushed into engagement with that terminal as for momentary flashing of the lamp in signaling. If continued burning of the lamp is desired, the operator first depresses 5 the push-button to move enlargement 23 out of locking engagement with opening 13 of the key hole slot, and then with his thumb pulls back on the housing to slide it backward along the case, thereby moving the stud into the narrowed end portion 10 of the double key hole slot, and at the same time bringing the stud into continuing engagement with battery terminal 6. Then, if the push-button be released by removal of the thumb, the lamp will continue 15 to burn with enlargement 23 frictionally engaging the inner face of the case immediately adjacent to the lower or end portion 14 of the double key hole slot. If then 20 the operator wishes to extinguish the light, he can merely push forward with his thumb on housing 15 until enlargement 23 snaps into the enlarged portion 13 of the slot, thereby opening the circuit at contact 6.

25 But, in addition to being able to flash the lamp as in signaling, and to burn the lamp continuously without continuing thumb pressure on the button, the present device has the advantage that the switch mechanism can be put in such condition 30 that inadvertent lighting of the lamp, as when the lamp is being shipped or carried about, is in large measure, avoided. To move the switch mechanism to safety position, it is necessary to depress the thumb button 18, thereby disengaging enlargement 35 23 from opening 13 of the slot, and to push the housing forward along the case until the enlargement snaps into opening 11 of 40 the slot. Battery terminal 6 is so positioned with respect to the key hole slot that when enlargement 23 is in opening 11, it will be beyond the end of terminal 6. Under these conditions thumb-pressure on button 45 18 will not close the circuit because stud 21 will not touch battery terminal 6. Furthermore, backward sliding movement of housing 15 is prevented because of the locking engagement between enlargement 23 and 50 opening 11. Therefore, to change the switch mechanism from this safety position to one in which the lamp can be lighted, it is necessary, first to depress the push-button, and then to pull back on the housing until enlargement 23 snaps again into opening 13. So complex a manipulation is not likely to 55 happen accidentally, and the lamp can readily be shipped or carried about with its battery in position and without danger of accidentally burning the lamp to no useful 60 purpose.

Although the embodiment illustrated in the drawing, and above described, is of the flat or vest pocket type, it will be understood 65 that I contemplate such changes in

arrangement and in details as are reasonably within the scope of my invention, as defined by the appended claims.

I claim:

1. In a battery hand lamp, the combination of a battery case, a housing mounted to slide longitudinally thereon, a leaf spring attached to said housing and a push-button contact carried by said spring and slidingly movable with said spring and housing, substantially as described. 70

2. In a battery hand lamp, the combination of a metal case having longitudinal slots therein, a housing mounted to slide in said slots, a leaf spring carried by said housing and a bush-button contact mounted on said spring and movable along said case with said spring and housing, substantially as described. 80

3. In a battery hand lamp, the combination of a battery case having a key hole slot, a housing mounted to slide longitudinally along said case, a leaf spring carried by said housing and a push-button contact attached to said spring and movable along 85 said key hole slot, substantially as described.

4. In a battery hand lamp, the combination of a battery case having a key hole slot, a battery therein having an exposed terminal, a housing mounted to slide longitudinally along said case, a leaf spring carried by said housing, and a push-button contact attached to said spring and movable in said slot into and out of engagement 95 with said battery terminal, substantially as 100 described.

5. In a battery hand lamp, the combination of a battery case having a key hole slot, a battery therein having an exposed terminal, a housing mounted to slide longitudinally along said case, a leaf spring carried by said housing, and a push-button contact mounted on said spring and having a shoulder for continuously engaging one 105 end of said key hole slot when continuing 110 connection with said battery terminal is desired. 110

6. In a battery hand lamp, the combination of a battery case having a double key hole slot, a battery within said case having an exposed terminal, a housing mounted to slide longitudinally along said case, a leaf spring connected at one end to said housing, a push-button contact mounted on the other end of said spring and having an enlargement engageable with either enlarged portion of the double key hole slot to prevent sliding movement of said housing, except when said push-button contact is depressed. 115 120

7. In a battery hand lamp, the combination of a battery case having a double key hole slot, a battery therein having an exposed terminal, a housing mounted to slide longitudinally along said case, a leaf spring 125 130

connected at one end to said housing, a push-button contact fastened to the other end of said spring, said push-button contact having an enlargement preventing sliding movement of said housing except when said push-button contact is depressed, said enlargement being adapted to underlie the lower end of said slot when continuing contact with the exposed battery terminal is desired.

8. In a battery hand lamp, the combination of a battery case, a housing mounted to slide longitudinally thereof, a leaf-spring having one end riveted to said housing and 15 a push button engaging the other end of

said spring, said push button being movable along said case with said spring and housing.

9. In a battery hand lamp, the combination of a battery case, a housing mounted 20 to slide longitudinally thereof, a push button mounted in said housing and moving therewith, and a leaf-spring having one of its ends rigidly attached to said housing and its other end engaging said push button, and means impeding free sliding movement of said housing and said spring along said case.

In testimony whereof I affix my signature.

GEORGE D. GALLAGHER.
